UNITED STATES PATENT OFFICE.

ANDREW SYLVESTER HUGHES, OF ACKLEY, IOWA, ASSIGNOR TO HIMSELF
AND HENRY CURTIS GREER, OF SAME PLACE.

MOLE-DITCHER AND TILE-LAYER.

SPECIFICATION forming part of Letters Patent No. 310,058, dated December 30, 1884.

Application filed April 26, 1884. (No model.)

To all whom it may concern:

Be it known that I, ANDREW S. HUGHES, of Ackley, in the county of Hardin and State of Iowa, have invented a new and Improved 5 Mole-Ditcher and Tile-Layer, of which the following is a full, clear, and exact description.

My invention consists of improvements in the construction of a mole plow or ditcher and tile-laying attachments in a combined machine, which said improvements are designed to provide a simple, cheap, and efficient machine for laying drain-tile, as hereinafter fully described.

Reference is to be had to the accompanying 15 drawings, forming part of this specification, in which similar letters of reference indicate corresponding parts in all the figures.

Figure 1 is a side elevation of my improved mole-ditcher and tile-layer. Fig. 2 is a longitudinal sectional elevation of the same. Fig. 20 3 is a plan view, and Figs. 4 to 8, inclusive, represent details in perspective view.

The plow-foot *a*, that makes the drain in which the tile are to be laid, consists of a 25 block of suitable material and dimensions, having an oval bottom, *b*, concave point *c*, and flat top *d*, said top being recessed at *e*, and having the lower end of the colter *f*, also the lower end of the attaching-bar *g*, fitted 30 to it and secured by the bolts *h* and *h'*, respectively, said colter and the bar *g* being firmly secured to the beam *i*, the colter passing through the beam and being fastened with a key, *j*, and the bar *g* being bolted to the beam 35 by the *T*-head *k*. The colter has an extension, *l*, of the foot forward of the connecting-bolt *h* and along a portion of the recess *e*, extending nearly to the front end of the plow-foot, by which the colter holds the plow-foot 40 more substantially against lateral divergence.

Between the colter *f* and the attaching-bar *g* there is a recess, *e*, where there is a gas-pipe, *m*, passing from foot *a* up through beam *i*, above which it has a faucet, and is connected to 45 hose-pipe *a'*, which extends back to water-tank *n* on the rear end of beam *i*, for lubricating the parts remaining against the earth, and to moisten the earth, so that it will be left smooth and will not obstruct the laying of the tiles. 50 In the recess *e* a hole, *o*, is made through the bottom of foot *a*, to admit the gas-pipe *m* to

let water on the bottom of the tile-layer, which consists of the tapered *U*-shaped mold-board *p* and the curved tube *q*, the mold-board being employed to keep the ditch open and support 55 the tube, and the tube being the chute down which the tile are conducted to the bottom of the ditch. The mold-board *p* is placed behind the plow-foot, with its curved bottom connected with the bottom of the plow-foot, also with 60 its vertical end ahead and lapping on the rear end of the plow-foot and on the attaching-bar *g*, so as to be riveted through both edges of the *U* to said plow-foot and bar, and the top of the mold-board bears against the under 65 side of the beam *i*, so that it is firmly stayed to give support to the chute *q*, which extends down through the beam *i* into the space between the top edges of the mold-board, and thence along within the curved rear edges, *s*, 70 to the lower back end, where it terminates coincident with the end of the mold-board. The edges *s* of the mold-board are bent before putting the parts together, so as to close around the rear side of the chute against a curved 75 bar, *t*, placed edgewise on the chute, and riveted together through said bar for a strong connection of the chute and mold-board. The front edges, *u*, of the mold-board are also to be closed together over the end of the plow-foot 80 sufficiently to conform to the thickness of the attaching-bar *g*, and so as to contract the front end of the mold-board within the thickness of the colter, so that it will follow the slit made by the colter and wedge out the sides of the 85 slit by its bulging sides. The mold-board and chute are also stayed by the braces *v*, extending obliquely up to and connected with the extension of the beam behind the mold-board. The mold-board *p* and chute *q* are yoked together at the rear end by the yoke *w*, bolted 90 to the side of the mold-board at *x*, and extending backward to the end, and thence over the top of the taper end of the mold-board and the chute, the yoke being made with a cross-bar, *y*, suitably curved, and having a recess, *z*, adapting it to the form of the mold-board, and the yoke is provided with knives *w'*, which run in the earth each side of the ditch for the purpose of holding the tile-layer down at the 95 heel.

For a means of drawing the ditcher, and for

regulating the action of the ditcher so as to gage it for making the bottom of ditch level or of uniform descent when the surface of the ground is irregular, I use a kind of sled, *c'*, having uprights *d'*, between which the beam *i* is fitted to rise and fall, and is suspended from a windlass, *e'*, by a chain, *f'*, to be wound up on the windlass or let out, according as the beam is to be raised or lowered, by turning the windlass with a crank, *g'*, which may be applied directly to the shaft of windlass *e'*, or may gear with it by a pinion, *h'*, and wheel *i'*, so that when the sled rises on ascending ground the beam may be lowered, or may be raised when the ground descends, to maintain uniformity of the level or grade of the bottom of the ditch. The pinion *h'* is to be locked to hold the windlass by a catch, *l'*. The beam *i* may be connected to the sled in any approved way for drawing the ditcher thereby, or the power may be hitched directly to the beam, with a separate connection of the sled to the power, so that the draft will be on the ditcher directly. The chute *q* is connected to the beam at the top of the same by a clamp, *k'*, extending around the rear side of the chute, and bolted down to the top of the beam, so as to bind the chute fast in the hole of the beam for the chute. The beam *i* has staples *n'* in the top, near the rear end, in which a hand-bar may be placed for lifting the machine and suspending it to shift it about above the ground.

Having thus described my invention, what I claim as new, and desire to secure by Letters Patent, is—

1. In a mole-plow, the combination, with the plow-point *a*, with its securing-standard *f* and the beam *i*, of the tapered mold-board *p*, and the curved chute *q*, seated or let into said mold-board, the rear edges of said mold-board being bent around the chute and bolted or secured to a curved bar, *t*, disposed upon the chute and extending up through the beam *i*, substantially as set forth. 45

2. In a mole-plow, the combination, with the tapered mold-board *p* and the beam *i*, of the curved chute *q*, let into said mold-board, the latter being bent around the chute and bolted to a curved bar, *t*, arranged along the chute, and the yokes *k'* and *w y*, substantially as and for the purpose set forth. 50

3. The yoke *w y*, having knives *w'* and recess *z*, in combination with the mold-board *p* and chute *q*, said yoke being attached to the sides of the mold-board at *x*, extending therefrom back to the end of the mold-board, and crossing over the same and the chute, substantially as described. 55

4. The cutters *w'*, attached to yoke *w*, and connected by said yoke to the mold-board and tile-chute, substantially as described. 60

ANDREW SYLVESTER HUGHES.
